CLAIM

The ornamental design for a design tools for drawing, as shown and described.

DESCRIPTION

FIG. 1 is a front perspective view of the design tools for drawing;

FIG. 2 is a front view of the design tools for drawing.

FIG. 3 is a rear view of the design tools for drawing.

FIG. 4 is a left view of the design tools for drawing.

FIG. 5 is a right view of the design tools for drawing.

FIG. 6 is a top view of the design tools for drawing; and,

FIG. 7 is a bottom view of the design tools for drawing.

The broken lines shown in FIG. 3 are included for the purpose of illustrating portions of the design tools for drawing and form no part of the claimed design.

1 Claim, 7 Drawing Sheets(56)
